CLAIM

The ornamental design for an electric bicycle, as shown and described.

DESCRIPTION

FIG. 1 is a top, front and left side perspective view of an electric bicycle showing my new design;

FIG. 2 is a bottom, rear and right side perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front elevation view thereof;

FIG. 8 is a rear elevation view thereof;

FIG. 9 is an enlarged view of portion 9 of FIG. 1 thereof;

FIG. 10 is an enlarged view of portion 10 of FIG. 1 thereof;

FIG. 11 is an enlarged view of portion 11 of FIG. 1 thereof;

FIG. 12 is an enlarged view of portion 12 of FIG. 2 thereof;

and,

FIG. 13 is an enlarged view of portion 13 of FIG. 4 thereof.

The dot-dash broken lines indicate the boundaries of the enlarged views and are used for annotative purposes only.

They do not limit or define the scope of the claimed design.
